R. H. PRATT.

WALL PAPER.

No. 17,672.

Patented Aug. 30, 1887

UNITED STATES PATENT OFFICE.

ROBERT H. PRATT, OF NEW YORK, N. Y.

DESIGN FOR WALL-PAPER.

SPECIFICATION forming part of Design No. 17,672, dated August 30, 1887.

Application filed July 5, 1887. Serial No. 243,472. Term of patent 3½ years.

To all whom it may concern:

Be it known that I, ROBERT H. PRATT, a citizen of the United States, residing at New York, in the county of New York and State 5 of New York, have invented a certain new and original Design for Wall-Paper; and I do declare the following to be a full, clear, and exact description of the invention, such as will enable others skilled in the art to which it applies to make and use the same, reference being had to the accompanying drawing, and to the letters and figures of reference marked thereon, which form a part of this specification.

The invention relates to certain new and 15 original designs for wall-papers, and is of the Moorish style, and will be hereinafter more particularly described and claimed, reference being had to the accompanying drawing, forming a part hereof, and in which is illustrated 20 the invention.

The design is made up of interlacing lines forming stars, a net-work covering the same, and other lines forming a many-sided plane.

To more particularly describe the design, 25 there are a number of lines, A, interlacing one another, as shown, to form a many-pointed star, and extended beyond the points of the star, as shown, so as to connect one star with another. Each star may be bounded by or 30 inclosed within a many-sided figure or plane—

say of hexagonal form—composed of lines B, which may be connected one with the other. A net-work composed of small lines C over-lies the figures of the pattern or design. The points of the star may be of gold color and 35 the center of copper color, while the lines composing the many-sided figure or plane may be of a steel-blue color. The ground is of a terra-cotta color, and blocks, D, of a copper color may be placed at divers points, as shown. 40

The design has also been described with considerable particularity, but only for fullness and clearness, without so far limiting the design as not to cover substantially the same and colorable imitations thereof. 45

Having described the invention, what is claimed is—

1. The design for wall-papers, consisting of the stars formed of interlacing lines, and an overlying net-work composed of small lines, 50 substantially as shown and described.

2. The design for wall-papers, consisting of the stars inclosed within a many-sided figure, substantially as shown and described.

In testimony whereof I affix my signature in 55 presence of two witnesses.

ROBERT H. PRATT.
